UNITED STATES PATENT OFFICE.

CHARLES A. FRENCH, OF DAVENPORT, IOWA.

FEED-WATER PURIFIER FOR BOILERS.

SPECIFICATION forming part of Letters Patent No. 250,519, dated December 6, 1881.

Application filed August 23, 1880. (Model.)

To all whom it may concern:

Be it known that I, CHARLES ALBERT FRENCH, a citizen of the United States, residing at Davenport, in the county of Scott and State of Iowa, have invented certain new and useful Improvements in Feed-Water Generators and Purifiers for Steam-Boilers; and I do hereby declare that the following is a full, clear, and exact description of the invention, which will enable others skilled in the art to which it appertains to make and use the same.

Heretofore feed-water for steam-boilers has been only partially purified by compositions tending to filter, absorb, or collect only a portion of the impurities, which, after a short time, lose their power of absorbing impurities and must be replaced or cleaned.

The object of my invention is to perfectly purify feed-water, and make the operation continuous without any perceptible loss of heat, and provide for a quick and speedy mode of removing the impurities as they accumulate; and it consists in forcing the feed-water into a chamber that is surrounded by steam, causing the feed-water to be speedily evaporated and condensed or absorbed by the steam in the boiler, leaving all the impurities in the chamber, where they can be blown out or speedily removed by taking off the heads. I attain these objects by the apparatus illustrated in the accompanying drawing.

The figure represents a side elevation of the boiler and apparatus, in which—

B is the boiler; e, the drum, into which the feed-water is pumped to be evaporated. f is the outer drum or jacket. The drum l is to work in connection with an injector, to have same result were the injector connected with the boiler; but this drum might be dispensed with if the pipe a is connected a little above the bottom, so as to leave some water in the drum e all the time.

To carry my invention into effect I place above the water-line a drum or chamber, e, (with or without a removable head of any desired shape or style,) and connect it at or near the bottom by a pipe, a, and extend upward higher than the drum or chamber, thence downward, and connect with the boiler above the water-line. The upward bend in the pipe is to prevent the feed-water that is forced into

the drum from running into the boiler by gravity. I circumscribe this drum or chamber with another steam-tight drum, chamber, or jacket, f, leaving a steam-space between. I then connect the top or near the top of this outer drum or jacket, f, by a pipe, b, with the boiler above the water-line, to supply the drum or jacket with live steam to keep the inner drum hot, and the bottom of the outer drum, chamber, or jacket I connect by a pipe, c, with the boiler any place, so that the steam that condenses in the space between the two drums will run into the boiler by gravity.

If the pipe a is large enough, the jacket f may be dispensed with, or the drum e may be placed below the water-line; also, the jacket f, if the condensed steam is kept pumped or drained out of the jacket f; also, the pipe a may lead out from the dome, if it is higher than the drum e, and the upward bend in the pipe a dispensed with by putting a porous partition in the pipe a, to keep the water from running through and yet allow the steam to go through.

The drum e may be dispensed with by making the pipe a large enough, and extending it upward in place of entering the drum e, and closing the top end of the drum e.

The feed-water is forced into the chamber e, (through the pipe d and drum l, which is always full,) the water rises in the chamber or drum e, and, being surrounded by steam, is soon heated as hot as the water in the boiler B, and hot steam coming from the boiler B through pipe a comes in contact with the water in drum e, absorbs it, and carries it over into the boiler B, leaving every particle of impurity in the inner drum, e, where, by opening a cock in the pipe m and closing the cock k, the sediment can be blown out. By opening the cock h the water can be blown through and rinse or wash it out; or steam may be allowed to blow through the pipe a for the same purpose; or the drum may be cleaned any time, without blowing off the steam in the boiler, by closing the cocks h i j k and taking off the heads. I have found that water in the drum e will be carried over in the shape of steam, (whether the cock h is open or closed,) and settle in the boiler.

The drum e and jacket f may be placed with their axes on a level plane, so the drum e can

be rotated to prevent the sediment from settling so fast, and the connection made through the axes by steam-tight joints, but the pipe *a* would have to have a downward bend, so as to bring the steam in contact with the water at the lowest point in the drum *e*.

The feed-water may be heated by exhaust steam or otherwise in any manner before it is forced or injected into the drum *e*, to save fuel.

- 10 I am aware that prior to my invention S. A. Goodwin and J. O. Joice, April 1, 1879, patented an apparatus consisting of a drum connected at the top with top of boiler and the bottom with the bottom of the boiler, and the 15 feed-water forced in at the top falls on a series of shelves, is heated more or less, the balance of the water falls into the bottom, stirs up and mixes with the sediment, and overflows and runs into the boiler through the pipe, running 20 always downward from the bottom of the drum with the bottom of the boiler, while mine has an upward bend; but theirs is not perfect in its operation, for the foam and spray produced will go into the boiler, and if the water is 25 pumped in too fast will chill the apparatus and run into the boiler with its sediment. It makes use of the steam to heat iron shelves, and depends on them while falling through the steam to heat the water.
- 30 It is evident that the drum *e* might be placed in chimney or smoke arch or exhausting steam, where the heat would aid the operation, and thus dispense with the outer drum or jacket, *f*. All the water that condenses in the jacket is 35 the same as so much pure water pumped into

the boiler. It will be seen that the pipe *a* can be connected anywhere on the drum *e*. As long as there is a place in the pipe that is higher than the top of the drum *e* the water cannot run into the boiler by gravity; also, that the pipe *b* might be dispensed with by making the pipe *c* large enough to supply steam and also carry off the condensed steam; or this jacket may be secured permanently to the boiler, and a series of holes in the partition, or no partition 45 between the bottom of the inner drum and the boiler.

I do not claim the process of evaporation and distillation.

I claim—

1. The process of purifying feed-water for steam-boilers, consisting in conveying the steam into a receptacle having a feed-inlet, whereby the water is generated into steam or absorbed by it, as described. 50

2. The process of feeding steam-boilers by confining the feed-water in a receptacle, and causing live steam to circulate into the feed-water, generating it into steam and conducting it into the boiler in the shape of steam, as 55 described.

3. The combination of a boiler with a steam pipe or passage leading to a receptacle having a feed-inlet and an outlet or passage for carrying the steam generated in the receptacle into 60 the boiler, as described.

CHAS. ALBERT FRENCH.
